DESIGN FOR A SURGICAL STITCHING INSTRUMENT OR SIMILAR ARTICLE

John D. Karle, Roselle Park, N. J., assignor to
The Singer Manufacturing Company, Elizabeth,
N. J., a corporation of New Jersey

Application February 11, 1942, Serial No. 105,770

Term of patent 14 years

To all whom it may concern:

Be it known that I, John D. Karle, a citizen of the United States, residing at Roselle Park, in the county of Union and State of New Jersey, have invented a new, original, and ornamental Design for a Surgical Stitching Instrument or Similar Article, of which the following is a specification, reference being had to the accompanying drawing, forming a part thereof.

The figure is a perspective view of a surgical

stitching instrument or similar article showing my new design.

The opposite side of the instrument is substantially the same in appearance as the side disclosed in the drawing.

I claim:

The ornamental design for a surgical stitching instrument or similar article, as shown and described.

JOHN D. KARLE.
